UNITED STATES PATENT OFFICE.

PETER DUFFY, OF NEW YORK, N. Y.

PIANO.

No. 913,711.

Specification of Letters Patent.

Patented March 2, 1909.

Application filed January 19, 1904, Serial No. 189,673. Renewed October 24, 1908. Serial No. 459,367.

To all whom it may concern:

Be it known that I, PETER DUFFY, of New York, in the county of New York, State of New York, have invented certain new and useful Improvements in Pianos, of which the following is a complete specification, reference being had to the accompanying drawings.

The object of my invention is to improve the tonal quality of a piano, by the introduction into its structure of a separator between its sounding board and its frame.

In ordinary piano construction the sounding board is provided near its edges with a strip of wood, in effect continuous, that is glued to the face of the sounding board next to the frame, and which is in turn secured, as by gluing, to the frame. In such construction, if the frame be of wood, the tone of the instrument is to a considerable extent absorbed by the wood. Attempts have been made to improve the tone by the employment of an iron frame, but the intended object has not been reached, for the reason that the metal frame presents too much dead weight to be vibrated, and the effect is to deaden, instead of to improve the tone of the instrument.

By my invention I obtain a distinctively characteristic quality of tone, which appears to be in large measure accounted for by the fact that the resonating mechanism of the instrument, although mechanically united to, is separated from the stress-sustaining mechanism or frame of the instrument in such manner and by such means hereinafter specified as produce characteristic variation in the tonal quality of the instrument.

What constitutes my invention will be hereinafter described in detail, and succinctly set forth in the appended claims.

In the accompanying drawing: Figure I is a perspective view of the frame of an ordinary upright piano, presented as an example of any piano frame, and to which my invention is applied; Fig. II is a front elevation of the subject-matter of Fig. I, showing the string plate with its strings and the sounding board partially broken away. Fig. III is a view similar to Fig. II, showing both the string plate and the sounding board removed, and exhibiting a frame embodying my invention, ready for the application thereto of the sounding board. Fig. IV is a section as on the line IV—IV of Fig. III,

showing simply in a diagrammatic way the relation thereto of the sounding board and string plate. Fig. V is a detail sectional view as on the line V—V of Fig. I clearly illustrating the relation of my invention to a piano structure familiarly known in the art.

Referring to the numerals on the drawings, 1 (compare for example Figs. II, III, and V) indicates the wrest plank and 3 posts or uprights, which, of any preferred number, with the usual spacing blocks at top and bottom, 65 constitute the typical wooden frame of a piano. The lower set of blocks referred to is indicated by the reference numeral 4 in Fig. III. The upper set are identical with the 70 lower set, except in point of location, and being of familiar use in the art, are not shown in the drawings.

5, 6, 7, and 8 (compare for instance Figs. II and IV) are consecutive, approximately contiguous strips, which constitute in effect the continuous marginal strip to which the sounding board 10 may be, as is usually the practice, glued. The employment of any ordinary or preferred material 75 so for the aforesaid marginal strip and sounding board is contemplated within the scope of my invention, the material usually employed being wood.

Having now, by reference to the drawings, 85 described by way of example certain piano construction familiar in the art, I next proceed, first reiterating that the structure referred to is shown and described only by way of example, to point out that which constitutes my present invention.

My invention, as has already been stated in general terms, consists of a separator incorporated in a piano structure between the sounding board and the frame, whereby the 95 separator is made to constitute in effect a division wall or line of partition, so to speak, between the resonating members of the instrument, represented by the sounding board, on the one hand, and the stress sustaining means thereof on the other hand, represented by the frame. The separator is indicated by reference numerals 11, 12, 13, and 14 (compare Figs. I and IV with Fig. III, each of its members being indicated 100 in the last named figure, and three of them being shown in Fig. I). The separator is so designated because it essentially separates the sounding board from the frame which carries it, the marginal strips 5 to 8 in- 105 110

clusive being glued to and constituting a part of the sounding board. The separator is therefore functionally a single member, and may be so constituted structurally, al- 5 though for convenience the separator may be divided into the several members specified and illustrated, if preferred. If divers members be employed to constitute a separator, they are preferably made non-contiguous, in 10 order to eliminate possible conflict of vibration between them. The metallic strips constituting the separator as illustrated, are shown as of angular cross section, which is a preferred, but by no means essential, detail. 15 As a convenient means of securing the separator to the frame of the piano, screws 15 at suitable intervals may be employed. They are preferably inserted through the sounding board marginal strip, or strips respectively, 20 as well as through the separator, or separator members, the sounding board being applied to the marginal strips and glued thereto after assemblage of the marginal strips with the separator and frame has been made. 25 The foregoing specification may serve to define my invention to one skilled in the art, but with a view of rendering its several relationships in a complete instrument more apparent, I illustrate also in the various 30 figures of the drawings various additional members of a complete instrument, all re- lated, to be sure, to my invention, but re- lated more or less indirectly thereto. In 35 Fig. II especially, but also in Fig. V, and diagrammatically in Fig. IV, I show a string plate 17, which, being applied, as shown, in front of the sounding board 10, is fixed in place upon the frame as by screws 18 and 19 (see Fig. V). It being necessary to prevent 40 actual contact between the string plate and the sounding board, I employ opposite to the marginal strips with which the sounding board is provided, spacing strips 20 which, although they may be dispensed with, afford 45 convenient means of compactly assembling the string plate with the sounding board, its marginal strips and separator upon the frame of the instrument. In Fig. V, in which the several relationships of the mem- 50 bers last above referred to are clearly illus- trated, I show also one of the strings, design- nated by the reference numeral 21, which, passing over the bridge 22 of the string

plate, and under a confining strip 23, is se- 55 cured to a hitch pin 24.

The structural features of my invention in illustrative form of embodiment thereof having now been specified, and the wide variability of the separator in point of form having also been specified, it remains only 60 to add that the material of which the sep- arator may be made may also be selected within a wide range, determined chiefly by its greater density as compared with wood, whence its characteristic quality, is derived. 65 Without intending to limit myself to a speci- fied material, I may mention steel, brass, aluminium, or metal of vibratile nature, and glass. Steel has been specified as the pre- 70 ferred material, because of its comparative cheapness and available utility.

What I claim is:—

1. In a piano, the combination with its frame, string plate, and sounding board, of a metallic separator in vibratory communi- 75 cation with said sounding board, and be- tween the frame and sounding board.

2. In a piano, the combination with its frame, string plate, and sounding-board, of a metallic separator in contact with said 80 sounding-board, and between the frame and sounding-board.

3. In a piano, the combination with its frame, string plate, and sounding board, of a continuous metallic separator in vibratory 85 communication with said sounding board, and between the frame and sounding board.

4. In a piano, the combination with its frame, string plate, and sounding-board, of a continuous metallic separator of angular 90 cross-section in contact with said sounding- board, and between the frame and sounding- board.

5. In a piano, the combination with a 95 frame, of a sounding-board, including a strip of the same material as the sounding-board proper and secured thereto, and a metallic separator in contact with the strip and be- tween the strip and the frame.

In testimony of all which I have hereunto 100 subscribed my name.

PETER DUFFY.
